UNITED STATES PATENT OFFICE.

WILLIAM C. McGRATH, OF BROOKLYN, NEW YORK.

DESIGN FOR A MIRROR SUPPORT.

Application filed March 21, 1929. Serial No. 30,578. Term of patent 3½ years.

To all whom it may concern:

Be it known that I, WILLIAM C. McGRATH, a citizen of the United States, and a resident of the borough of Brooklyn, county of Kings, city and State of New York, have invented a new, original, and ornamental Design for a Mirror Support, of which the following is a specification, reference being had to the accompanying drawings, forming a part hereof.

Referring to the annexed sheet of drawings,

Fig. 1 is a rear elevation of a mirror support, showing my new design; and

Fig. 2 is a side elevation thereof.

I claim:

The ornamental design for a mirror support, substantially as shown.

WILLIAM C. McGRATH.
